BURNER

John E. Greenawalt, New York, N. Y.

Application February 9, 1934, Serial No. 710,397

5 Claims. (Cl. 158—77)

My invention has relation to improvements in burners particularly adapted for the burning of liquid fuel, such as oil, and it consists in the novel features of construction more fully set forth in the specification and pointed out in the claims.

The present invention is an improving departure from my co-pending application Serial No. 685,820, filed August 19, 1933, and as in said application the essential features of the invention are directed to the means for carbureting and distributing the fuel over a wide area so that combustion may be complete and productive of intense heat.

Among the objects of the invention are the following: the provision of a burner embodying a fuel distributing head for subdividing the fuel into minute particles and mixing air with said minute fuel particles before they are discharged from the distributing head to obtain not only a thorough atomization but also partial vaporization of the fuel; the provision of a secondary supply of air on both sides of the surfaces from which the mixed air and fuel discharge to insure ample air to support the combustion of the fuel; the forceful ejecting of the mixed air and fuel from the orifices of the distributing head to prevent combustion within the head; the protection of the burner against the heat of the combustion chamber by the provision of a suitable shield held in spaced relation with said head, and the provision of means for circulating air through such space to keep down the temperature of the shield, thus protecting the distributing head and prolonging the life of the shield; the arrangement of the fuel discharge ports to expedite reception of the fuel and effect a radial discharge thereof to expel the mixed fuel and air from the distributing head before ignition thereof; and such other objects and advantages as are inherent in the invention and which will become more apparent from a detailed description of the invention in connection with the accompanying drawings, in which:

Figure 1 is a side elevation of my improved burner mounted for operation in connection with a down draft furnace, a part of which is shown in longitudinal section; Fig. 2 is a middle vertical longitudinal section through the burner and that part of the furnace immediately adjacent the burner; Fig. 3 is a plan view of a portion of the furnace showing the annular air-control damper for regulating the air supply to the furnace; Fig. 4 is a horizontal cross-section taken on a plane indicated by the line 4—4 of Fig. 2; Fig. 5 is a horizontal cross-section taken through the fuel

distributing head on a plane indicated by the line 5—5 of Fig. 2; Fig. 6 is a bottom plan of a fragment of the distributing head disk 2; and Fig. 7 is a cross-sectional detail taken through the furnace damper on the line 7—7 of Fig. 3.

Referring to the drawings, B represents my improved burner positioned in the opening O in the roof R of the down draft furnace F, the fuel distributing head 1 of the burner projecting into combustion chamber C. The burner B is carried by a suitable housing H which is supported by flanges f, f on what may be termed a wall box W positioned in the opening O and resting on the furnace roof R. The fuel distributing head 1 comprises a circular disk 2, at the center of which is a perforated boss 3 in which is securely fixed a tube 4 which extends upwardly therefrom and is rotatably mounted within a bearing member 5 supported from the top 6 of the housing H. The bearing member comprises an upper cylindrical section 7 and a lower section 7', and in the upper section are ball bearings 8 and 8' in spaced relation which take both the vertical and lateral thrust of the tube 4 when the latter is rotated, as presently to appear. A fuel receiving chamber 9 is formed around the boss 3 of disk 2 by an annular member 10 having a flanged portion 11 and a central frusto-conical portion 12 which encircles the boss 3 and the lower part of tube 4. The boss 3 is shouldered at the upper part of its inner surface so as to provide an oil well 13 around the tube 4, into which the fuel oil is discharged from a feed pipe 14 within the housing H and connected with a pipe 15 passing out of the housing to a suitable source of fuel supply (not shown). A series of bosses 16 extend entirely around and inwardly from the periphery of the disk 2 on the upper surface thereof, and a series of bosses 17 extend entirely around and inwardly from the periphery of the lower surface of the disk 2, and the flange 11 of the member 10 is securely bolted against the bosses 16 while a circular plate or shield 18 (slightly conoidal) is bolted against the bosses 17. A single set of bolts 19, uniformly spaced, secure all three of these distributing head members in intimately assembled relation. The bosses 16 are shaped to provide angular passages or ports 20 between them. The inner parts a of the ports communicating with the chamber 9 approach tangency to the wall 12 of the chamber 9, and the outer parts b of the ports are radially disposed with respect to the periphery of the distributing head 1. The bosses 17 which serve to hold the plate 18 in spaced relation with disk 2 are shaped similarly to the bosses 55

- 16, and, of course, the passage-ways 21 between said bosses would be shaped similar to the passage-ways or ports 20. The reason for shaping the passage-ways will presently appear.
- 5 On the upper surface 22 of flange 11 are a plurality of radially disposed ribs or vanes 23 which serve as fan blades for drawing air to the periphery of the distributing head 1 when the burner is in operation. An air-gate or damper 10 24 is provided in the wall of housing H and is equipped with a notched rack 25 pivotally mounted on a pin 26 near the lower end of the gate 24 so that it may engage a lip 27 projecting from flange 11 to hold the gate in any one of a series of 15 open positions for controlling the amount of air admitted into the housing H. As explained above, the fuel distributing head is rotatably supported by the bearing member 5 and is adapted to be rapidly rotated by means of a motor M to 20 shaft 28 of which tube 4 is directly connected by means of a coupling comprising members 29 and 30 secured together in spaced relation by means of bolts 31 and threaded sleeves 32. The provision of the space 33 between the coupling members 29 and 30 permits air to enter the upper end 25 of tube 4 through which it passes to the inner surface of plate 18 taking up much of the heat from said plate before discharging from the passage-ways 21 between bosses 17. This circulation of air over the inner surface of plate 18 thus serves to hold down the temperature of said plate so that it will not be destroyed by the heat 30 of the combustion chamber.
- In order that there may be an adequate supply of air within the combustion chamber C to 35 maintain combustion of the fuel throughout said chamber a plurality of air intake openings 34 are provided in the roof R of the furnace F, said openings coinciding with openings 34' in the top plate 35 of the wall box W. An annular damper plate 36 is mounted on the plate 35 above the openings 34', said plate 36 being confined by means of a series of evenly spaced rollers 37 mounted on studs 38. The plate 36 is 40 provided with a plurality of openings 39 of the same size and spacing as the openings 34' so as 45 either to close the openings 34' or entirely open them by the proper rotation of the plate 36 by means of a handle 40 provided for this purpose.
- 50 The amount of movement of the plate 36 is limited by a pin 41 projecting from the plate 35 into a slot 42 at the margin of the plate 36.
- It will be observed that the bosses 16 are 55 widened slightly toward the periphery of disk 2, and the passage-ways b are correspondingly reduced in size toward the periphery. The purpose of this is to limit the width of the oil passages toward the periphery of the disk and thereby obtain a maximum centrifugal action on the 60 stream and discharge it with sufficient velocity to throw the fuel particles away from the disk and thus prevent ignition of the fuel in the passage-ways. The purpose of having the inner part a of the passage-ways somewhat tangential 65 to the wall 12 of the chamber 9 is to give greater freedom of entry of the oil particles to the passage-ways as the disk is rapidly revolved in the direction of the arrow (Fig. 5). However, the passage-ways must not be tangential at their outlets because it is one of the objects of the invention to expel the mixed fuel and air from the distributing head as far as possible and a tangential outlet would cause the fuel mixture to hug the periphery of the distributing head. It is for 70 this reason that the outer parts b of the passage-

ways are radially disposed with respect to the distributing head. This arrangement also prevents the formation of eddy currents within the distributing head 1 whereby the flames outside of the head might be drawn into the head and cause 5 premature combustion.

The action of my improved oil burner is as follows. The oil is delivered from the pipe 14 into the oil well 13 around the tube 4 from which it is expelled by centrifugal action after which 10 it impinges on the inner conical surface of the wall 12 of the receiving chamber 9. The centrifugal action causes the oil to spread out over this surface into a very thin film which becomes more atomized as the oil approaches the inside 15 of flange 11 where it enters the passage-ways 20 between bosses 16. Of course, air is mixed with the oil as it discharges from the oil well 13 and when the oil reaches the passage-ways 20 it is further broken up and mixed with air by the 20 fan action of the bosses 16. Obviously, the passage-ways 20 all receive approximately the same amount of oil and air on account of the uniform distribution thereof by the centrifugal force; and on account of the radial disposition of the outer 25 portions b of the passage-ways 20 and the constricted outlets of the passages which serve as nozzles, this fuel mixture is ejected under considerable force from said passage-ways by the time the oil passes through the passages 20 and 30 is about to be discharged therefrom. It is not only uniformly distributed around the fuel distributing head 1, but is also in a very fine state of division, or atomization, so that it may be very easily and quickly vaporized the instant it enters 35 the combustion chamber C. In addition to the air that is discharged from the passages 20 with the oil there are two other supplies of air to insure thorough atomization and combustion at the distributing head. The one supply of air is 40 created by the fan blades 23 projecting upwardly from the flange 11 and enters the combustion chamber C in sheet form immediately above the fuel mixture. The other air supply is discharged 45 from the passage-ways 21 between disk 2 and plate 18 and enters the combustion chamber C as a plurality of jets immediately below the fuel mixture issuing from the passage-ways 20. The bosses 17 serve as fan blades to maintain a high 50 velocity circulation of the air through passage-ways 21. Thus the fuel mixture enters the combustion chamber C between two air supplies so as to insure sufficient air to completely atomize the fuel and obtain an effective ignition. Of course, 55 combustion is continued in the combustion chamber and additional air that might be needed to further the combustion in said chamber may be obtained by regulating the damper plate 36. Thus there are three air supplies for the fuel, the primary air supply entering the combustion 60 chamber C intimately mixed with the fuel from the distributing head 1, and the secondary air supply entering the combustion chamber on both sides of the spray of mixed fuel and air issuing from the distributing head 1. I have found in 65 practice that the amount of primary air should be between 20% and 50% of the entire air supply required for complete combustion, the amount of secondary air, of course, not being so critical provided there is sufficient secondary air to complete the combustion of the fuel. The velocity with which the secondary air passes into the combustion chamber C is increased by the vanes 70 23 on the flange 11. The supply of air entering 75 the combustion chamber below the fuel mixture

also serves the purpose of keeping down the temperature of the plate 18 which serves as a protecting shield for the burner to prevent the destruction of the same from the intense heat of the combustion chamber C.

5 The high peripheral speed of the distributing head 1 causes an intense turbulence in the combustion chamber C. This turbulence expedites the mixing of the atomized fuel and the air so that I obtain an explosive mixture almost as soon as the fuel and the air enters the combustion chamber C. Therefore, combustion proceeds immediately and continuously as the mixed gases are whirled downwardly through the combustion 10 chamber.

15 Having described my invention, I claim:

1. In a burner for liquid fuel, a fuel distributing head, means for feeding fuel into the head, fan blades within the head for forcing air there- 20 through, an impeller associated with the head, means for rotating the distributing head, a disk supported in spaced relation with said distributing head to protect the same from the heat of the burning fuel, and means for circulating air 25 in the space between said disk and the head.

2. In a burner for liquid fuel, a fuel distributor and impeller in the general shape of a disk having a central chamber, said impeller having an air inlet, a plurality of radially disposed blades 30 circumferentially spaced around said central chamber, some of said blades forming fuel pas- sages between them and other of said blades forming air passageways between them, a plurality of fan blades on one side of the impeller, a disk on 35 the other side of the impeller to shield the same from the heat of the burning fuel, and means for introducing fuel to said chamber.

3. In a burner for liquid fuel, a fuel distributor and impeller in the general shape of a disk having a central chamber, a plurality of radially disposed blades circumferentially spaced around said central chamber, said chamber having an inlet for air, means for introducing fuel into said chamber, said blades forming fuel and air passages between them, a plurality of fan blades on one side of the impeller, a disk on the other side of the impeller and spaced therefrom to shield the impeller from 10 the heat of the burning fuel, and a plurality of radially disposed blades circumferentially spaced between the impeller and said shield disk, said blades extending inwardly from the periphery of the impeller.

15 4. In a burner for liquid fuel, a fuel distributing head, said head comprising a hollow disk-like member having an annular chamber and a hollow marginal flange communicating therewith, an annular fuel reservoir within said chamber, means 20 for feeding fuel to said reservoir, the outer wall of said chamber being inclined outwardly and downwardly, and means for rotating said head and the fuel reservoir, to expel the fuel therefrom by centrifugal action.

25 5. In a burner for liquid fuel, a fuel distributing head, said head comprising a hollow disk-like member having an annular chamber and a hollow marginal flange communicating therewith, an annular fuel reservoir within said chamber, mean for 30 feeding fuel to said reservoir, the outer wall of said reservoir inclining outwardly and upwardly, and the outer wall of said chamber being inclined outwardly and downwardly, and means for rotating said head and the fuel reservoir, to expel the fuel 35 therefrom by centrifugal action.

JOHN E. GREENAWALT.
